ESCAPEMENT AND PENDULUM MECHANISM

Application filed January 5, 1931, Serial No. 506,690, and in Germany January 7, 1930.

My invention relates to the construction of clocks and more especially to an improved escapement and pendulum mechanism for clocks in which extreme accuracy is desired.

5 As a matter of fact known to practitioners in this field spring driven clocks of which the train of wheels is cooperatively connected with the pendulum through a so-called anchor escapement do not keep strictly correct time but will gain or lose in accordance with the varying motive power of the spring.

In order to render this lack of uniformity less noticeable it is common practice to regulate clocks of this type in the maker's shop 15 by setting those parts controlling the work of the escapement and its reaction upon the pendulum in such position to each other that the gain of time is to some degree compensated by the loss; for instance a clock thus 20 regulated which—when its spring is fully wound up is ready to go for two full weeks—will first gain in quickly increasing and gradually decreasing measure until the end of the first week, will then keep correct time for 25 a very short while, and will finally lose in rapidly increasing measure during the second week.

However this simple yet somewhat rough method of regulating clocks obviously insures by no means an absolutely correct and 30 precise keeping of the time by the clock; and the more because the clocks are usually wound up at irregular intervals.

35 The principal object of this invention is to provide an improved pendulum controlled escapement of relatively simple design for spring actuated clocks which ensures a greater uniformity of their keeping time 40 work.

Other objects of this invention and advantages obtained thereby will become apparent hereinafter.

The nature and scope of the invention are 45 briefly outlined in the appended claims and will be more fully understood from the following specification taken together with the accompanying drawing in which:

50 Fig. 1 is a fragmentary side elevation showing the principal parts of the escape-

ment and pendulum mechanism by way of an example,

Figs. 2 and 5 are fragmentary views of the escapement and pendulum mechanism from the rear side, their principal parts being 55 shown in different characteristic positions,

Figs. 3 and 6 are cross sections taken along line I—I in Fig. 1 and showing the escapement in two characteristic positions,

Fig. 4 is a side elevation showing in an 60 enlarged scale the leaf spring and accessory parts interconnecting the pendulum and the escapement in accordance with this invention.

The escapement is of the pendulum controlled type and comprises the escape wheel *q* and an oscillating anchor *r* of known design. The escape wheel *q* is cooperatively connected in the usual manner with the main spring of the clock through a train of 70 wheels,—not shown—which are rotatably mounted between and carried by the side plates *k*, *k*² of the clock.

At one end of the oscillating shaft *g* on which the anchor *r* is rigidly mounted, a control lever *i* is adjustably secured, which is free to swing between two studs or abutments *h*, *h*², the latter being fixed close to the lower end of said lever, so as to check its swinging movements and in turn those of the 80 anchor *r* in specific positions.

The distance of the studs *h*, *h*² from each other is so chosen that the anchor *r* is arrested immediately after its respective pallets have become engaged with or disengaged 85 from the teeth of the escape wheel *q*, i. e. after the anchor has swung through an angle *x* from its neutral position, as indicated in Figs. 5 and 6.

In this way the impulse giving action transferred from the escape wheel *q* upon the energy transmitting pallet of the anchor *r* and also the reaction from the locking pallet of the anchor upon the escape wheel are both definitely limited as to their timely duration, 95 strength and the resulting frictional resistance.

In other words those factors in the work of the escapement and its accessory parts which otherwise by reason of the varying 100

motive power of the main spring make for non-uniformity in the time keeping of the clock have been cut down to a minimum with the result that the pendulum, receiving 5 pulses of substantially equal strength will show amplitudes of uniform-extent in its swinging movements.

Another feature of this invention which contributes to the uniformity of the time 10 keeping work of the clock consists in the specific design of the pendulum proper and its cooperative connection with the escapement:

On the oscillatory shaft g , carrying the anchor r of the escapement, a lever f is attached 15 which is rigidly connected with a leaf spring a , supporting the pendulum p , through a connecting rod e and a U-shaped clamp b, c , the latter embracing the leaf spring a in their middle section from both sides.

20 The pendulum supporting spring a is held at its upper end by a pin n extending through a slotted support m which is attached to the side plate k of the clock.

The position of the slotted support m carrying the leaf spring a is so chosen that the axis 25 of the oscillatory shaft g of the anchor r coincides with the virtual bending centre around which the upper part of the leaf spring a flexes, and which is indicated in Fig. 30 4 by the upper dot and dash line and in Figs. 2 and 5 by an imaginary point $g2$.

The escapement and the pendulum cooperate in the following manner:

The pendulum p while moving from its 35 zero position through the angle x referred to above, swings around the upper part of the leaf spring a , the effective length of the pendulum being then equal to $L2$.

When the anchor or detent r reaches one of 40 its extreme positions, referred to above, lever f jointly with the connecting arm e and the clamp b, c will arrest simultaneously the leaf spring a which has been slightly twisted in its middle section with the result that the pendulum p is now free to move on its own account, swinging through a supplementary angle y as seen in Fig. 5.

The pendulum will swing during this second period of its movement around the lower 50 part $a2$ of the leaf spring, the bending line of the latter being indicated also by a dot and dash line in Fig. 4; the effective length of the pendulum in this latter case is equal to L .

55 The difference between the two pendulum lengths $L2$ — L viz the distance between the two virtual bending centres of the spring $a2$ should be rather small when compared with the total length of the pendulum P . Good results will be obtained with springs in which the distance of the upper bending centre from the lower one is substantially equal to

$$65 \quad \frac{e \cdot a^2}{2 \cdot 1 + a}$$

meters in which equation e is the effective pendulum length in meters and a the arc in angular measure of the swinging amplitude of the pendulum.

Various changes and modifications may 70 suggest themselves to those skilled in the art of clock making as regards the design and cooperation of escapement and pendulum mechanism having the features described above, and in the shape of their component parts, without substantially departing from the spirit and the leading ideas of my invention.

Whereas the invention has been shown and 75 described with reference to a recoil escapement of the so-called "anchor" type, widely used—e. g. in clocks made in the Black Mountains of southern Germany—other types of escapements such as dead-beat and non-recoil types including "Graham" escapements may 80 be used to equal advantage. Escapement and pendulum mechanisms of the type described with reference to coil spring actuated clocks 85 may be used without changing the design and mode of cooperation of their component parts also for weight actuated clocks.

What I claim is:

1. A mechanism of the class described 90 comprising a stationarily mounted escape wheel, a pendulum, a leaf spring of relatively short length by which the pendulum is suspended, an anchor cooperating with the escape wheel and being pivotally mounted so as to swing around a fixed axis, means for 95 limiting the swinging movements of the anchor to predetermined amplitudes, a support from which the pendulum spring is suspended, a clamp of relatively short length attached to the middle section of said spring, 100 energy transmitting means rigidly interconnecting the swinging anchor and the said clamp, causing the latter to perform swinging movements of limited amplitudes corresponding to those of the anchor, the total length of the spring and of its clamp being 105 so chosen that the spring will be periodically slightly twisted by said clamp and said energy transmitting means respectively around two virtual bending centres, one of which being above and the other below the clamp, the upper bending centre substantially coinciding with the axis around which the anchor and the said energy transmitting means swing.

110 2. A mechanism of the class described and having the features outlined in claim 1, in which the said energy transmitting means comprise a lever, adjustably mounted on the axis of the anchor, a connecting rod horizontally extending from said lever and a U-shaped member rigidly interconnecting 115 said rod and clamp.

In testimony whereof I have signed my name to this specification.

GOTTLOB JAISSE.
